INC. ATTORNEY

face of the casing 10 and be resiliently retained in non-revolvble contact therewith during the raising and lowering of the cup member 16.

When the device is in the form shown in Figures 2 and 3, with a lipstick 19 inserted within the cup 16, the revolution of the base 13, the casing 10 being held from revolution will cause the guide pins to move upwardly through the spaces 15, 15 between the convolutions of the helical member 14. But as the guide member 17 is resiliently retained from revolution, the cup 16 will move upwardly with it without revolution within the casing 10, thus preventing the troubles incident to the operation of devices of this character in which the commodity carrier revolves within the casing.

It will be noted that the guide pins 18, 18 connect the cup 16 and the guide member 17 and that these pins 18, 18 pass through and move through the spaces 15, 15 of the helical member 14, which is positioned between the cup 16 and the guide member 17 and that, therefore, it is impossible for these pins to leave the spaces 15, 15 during the operation of the device.

I do not limit myself to the size, shape, number, material or arrangement of parts specifically shown and disclosed as these are given solely in order to describe the devices of my invention.

What I claim is:

A container comprising a casing, a revoluble base member carried by said casing; a commodity carrier within said casing; a resilient guide member spaced from said commodity carrier and slidably and frictionally contacting the inner wall of the casing, and adapted to be retained from revoluble movement during the longitudinal movement of said commodity carrier; a helical member carried by said base member and having spaced convolutions, said helical member being positioned between said commodity carrier and said resilient guide member; connecting means secured to said resilient guide member passing through a convolution of said helical member and connected with said commodity carrier, and a cover for the device.

JOSEPH LESHIN.
